INVENTOR

Maxwell C. Frank

UNITED STATES PATENT OFFICE.

MAXWELL C. FRANK, OF PIEDMONT, CALIFORNIA.

ATTACHMENT FOR ELECTRIC SWITCHES.

1,257,473.

Specification of Letters Patent. Patented Feb. 26, 1918.

Application filed January 31, 1917. Serial No. 145,782.

To all whom it may concern:

Be it known that I, MAXWELL C. FRANK, a citizen of the United States, residing at Piedmont, in the county of Alameda and 5 State of California, have invented certain new and useful Improvements in Attachments for Electric Switches, of which the following is a specification.

My invention relates in general, to that 10 class of attachments having self-luminous indicating or guiding means thereon, for rendering the location of objects visible in the dark, and more particularly to an attachment of the character mentioned, for 15 application to electric switches or the like, which will indicate the location of the switch when sought for at night or in dark situations.

A specific object of my invention is to provide 20 a simple, efficient, self-luminous attachment, that can be readily applied to new and existing ordinary electric switches of the single or gang pattern, by the same common, ordinary attaching screws used for securing 25 the switch-plate to the switch.

With this and other objects in view, my invention resides in its novel arrangement and construction which I shall now fully describe by reference to the accompanying 30 sheet of drawings, in which—

Figure 1 is a plan of a push-button electric switch, with my luminous attachment applied to its switch-plate with the latter's own attaching screws.

35 Fig. 2 is a partial sectional elevation of Fig. 1 taken centrally, and shows in addition the switch box set in a recessed wall and secured thereto.

Fig. 3 is a plan of my attachment, the 40 dotted portion being the illuminated area.

Fig. 4 is a sectional elevation of Fig. 3 taken centrally.

Fig. 5 is a cross-section of Fig. 3 taken on the line A—B.

45 Fig. 6 is a plan of a modification of my invention applied similarly and to a similar switch as that shown in Fig. 1.

Fig. 7 is a cross-section of my attachment of Fig. 6 taken on the line C—D and may 50 also be taken as a cross-section on the line E—F of Fig. 3.

Similar numerals of reference indicate corresponding parts in all the figures, in which—

1 is a common switch-plate for an ordinary electric switch 2, and is secured to the same by the common attaching screws 3, which also secure my invention to the said switch-plate. 4 is a glass or other transparent or translucent member, preferably 55 made in the form of a plate or facing, with an oval aperture or other suitable opening, wholly or partially encompassing a pair of electric switch buttons 5. The walls or periphery of the aperture or opening, are 60 shown with a pronounced slope to allow for 65 free clearance for the finger in depressing the said switch buttons.

The transparent member 4, is itself encompassed by preferably a stamped, formed 70 and fitted suitable metallic framing of sheet metal, which may be applied to the switch-plate 1, by removing the aforesaid attaching screws 3 and positioning the said framing 75 on the screw-holes of said plate and rescrewing the latter with the superimposed framing, to the switch box 2.

6 is luminous material of any efficient make and is shown dotted in the several plan views and presents the preferable area 80 of the luminous facing that will be visible in the dark and in the various cross-section views it is represented by the heavy black lines. The transparent member 4 is by preference, recessed on its bottom face to receive 85 the luminous material, which recess also affords general protection for the latter material; on its top face I prefer to construct two recesses, one adjacent to each side edge adapted to engage the strips 7 of the framing. Along the end edges of said member 4, 90 the framing is continued and bent or otherwise formed over said member, forming cross-strips 8, shown more clearly in Fig. 4, thus the strips 7 and 8 rigidly incase the said 95 member 4. The said cross-strips 8 also form end walls for the recess, thus completing the incasing of the luminous material as well.

To each cross-strip 8 an extension lug 9 is formed having a suitable aperture 10, the 100 surrounding edge of which may be dished downwardly as shown in Figs. 2 and 4, for

ready positioning in the screw-holes of the switch-plate 1 when my device is applied to the latter.

The attaching screws of the plate 1, when being tightened to draw the framing over the transparent member 4 to securely bind the whole in position, are liable to break or fracture the said member, especially if it is glass and particularly so if the surface of the switch-plate or glass facing is not perfectly level or even. In such cases I may prefer to secure or place a sheet or shim of yielding or compressible material 11, such for example as rubber, paper or the like over the bottom face of the member 4, to take up the unevenness or imperfections of the joint, when the said attaching screws 3 are tightened. The sheet 11 is also a protector for the luminous material by serving as a cover for the recess.

In some cases I may prefer to illuminate a different portion of the switch, for example, in Fig. 6 which is a modification of my invention, the portion between and adjacent to the switch buttons 5 may be illuminated as shown by the dotted area. In this case the transparent member 4 but partially encompasses the buttons, and likewise do the lugs 9 of the framing, and the said member 30 is of different form and shape to that of Fig. 1, and enables a much less amount of the luminous material to be used, which is advantageous if a superior and expensive quality is desired. The facing is supported by the strips 7 of the framing similar to the method employed as in Fig. 1.

Fig. 7 is a cross-section of the modification shown in Fig. 6 taken centrally on the line C—D. The strips 7 are shown engaged in the recesses on the top face of the transparent member 4 and the luminous material 6 on its bottom face is represented by the heavy black line; 11 is a resilient supporting shim and also a cover for the luminous material. Fig. 7 may also be taken as a cross-section on the line E—F, of my attachment shown in Fig. 3.

Having described my invention and an embodiment of it, it is to be understood that the same covers other variations which come within the spirit of the invention and which are within the scope of the claims.

What I claim as new and desire to secure by Letters Patent of the United States, is the following, to wit:

1. An attachment for an electric switch plate, comprising a transparent member covering a luminous material and a flexible framing encompassing said member; said framing adapted to be drawn to position on said plate and secured thereto.

2. An attachment of the character described, comprising a transparent facing recessed on its bottom face, luminous material

in said recess, a framing adapted to encompass said facing, and said framing provided with lugs having means thereon for application to an electric switch.

3. An attachment of the character described, comprising a luminous facing provided with an opening for encompassing a pair of switch buttons, a fitted framing about the edges of said facing for holding the same therein, a pair of extension lugs formed on said framing with means thereon, whereby the framing can be attached to an electric switch.

4. An attachment for electric switches, comprising a transparent plate having luminous material applied thereto, said plate adapted to encompass a pair of switch buttons, a framing adapted to encompass said plate to rigidly incase same and said framing provided with a pair of lugs, each lug having an aperture with downwardly projecting edges adapted to readily position the said framing on the switch-plate of the switch and be secured thereto.

5. An attachment of the character described, comprising a framing fitted about the edges of a transparent plate to inclose same, and adapted to be secured to an electric switch, luminous material applied to the bottom face of said plate and a yielding shim covering said luminous material, and said shim adapted to resiliently support the said plate.

6. An attachment for electric switches, comprising an integral framing and a luminous facing, the said framing provided with strips for incasing the said luminous facing, and also with an extension lug at each end of said framing, each lug having an aperture for adapting the said framing and the incased facing to be rigidly secured to said switch.

7. A transparent plate having a recess on its bottom face for the reception of luminous material, and a pair of recesses on its top face along and adjacent to each side edge for the reception of supporting means therefor.

8. A self-luminous plate, provided with openings to allow for the insertion therethrough the buttons of an electric switch, and said plate adapted to surmount and be attached to said electric switch by the plate attaching means provided for said switch.

9. An attachment for a switch plate composed of a transparent member and a flexible holding frame therefor; said member having self-luminous means applied thereon for rendering the location of said plate visible in the dark, and said frame provided with an aperture for the insertion of means to draw the frame in position on said plate, and hold the attachment thereto.

10. In combination with a switch plate, a

superimposed flexible framing and a transparent member provided with an illuminated area; said member supported by the framing and said framing adapted to be drawn and secured to position on said switch plate by the attaching means carried by said plate.

In testimony whereof I have affixed my signature, in the presence of two witnesses, this 24th day of January, 1917.

MAXWELL C. FRANK.
